DEVICE FOR EXAMINING LIQUIDS

John K. Kolb, Detroit, Mich.

Application June 21, 1935, Serial No. 27,778

4 Claims. (Cl. 88—14)

The objects of my invention are to provide a readily portable means of quickly determining by visual inspection the condition of the motor oil of an internal combustion engine, and using a sample holder that is inexpensive and of such design as to facilitate the taking of the sample. The sample holder is made of flexible transparent material, such as clear Celluloid, which is shaped to form a funnel when the open corners are pressed lightly between the fingers, readily receiving a few drops of oil from the bayonet gauge which is stock equipment on motor cars, and eliminating the need of additional facilities to make the test.

15 The invention is illustrated by the accompanying drawing, in which:

Figure 1 is a front view of the oil examiner, the dotted line indicating the position of the sample holder at the time of examination. Right and 20 left halves of the oil examiner are similar.

Fig. 2 is a top view partly in section of the oil examiner.

Fig. 3 is an end view, as seen from the left of Fig. 1.

25 Fig. 4 shows the sample holder.

Fig. 5 shows a top view of the sample holder when opened by slight pressure of the fingers.

Referring more in detail to the drawing, Figures 1, 2 and 3, the following description is similar for 30 both right and left halves: The case 1 is a metal box, having a handle 2 at the top. At the back of the case are mounted two dry cells 3, insulated from the case 1 by insulating fiber 4. A metallic strip 5 attached to fiber insulation 4, is used as a

35 conductor from one of the battery terminals. The insulating fiber partition 6 has a metallic strip 7 attached to it. This strip 7 is made in the shape of a right angle, forming a light spring contact at one end with strip 5, and extending downward

40 to form a contact with the terminals of electric bulbs 8 and 9. These bulbs are threaded into reflectors 10 and 11 which are stamped out of a single piece 12, side extensions of which form a contact with case 1, as at 12, Fig. 2. The sliding

45 switch 13 is shown in its off or neutral position in Fig. 1. If moved to the left, the circuit is completed with the left battery and the two electric bulbs in the left half of the box are lighted. If moved to the right the two bulbs at the right, shown as 8 and 9, are lighted. The piece of

50 ground glass 14 is used to diffuse the light from the electric bulbs and also act as a support for the electric displays, as shown at 15, and also in front of electric bulb 9.

55 The contents of the case are held in place by

the cover 16, which has openings above and below at both the right and left sides. The lower openings are rectangular, as shown at 15, for the aforementioned electric displays. Appropriate wording for the sign at the right, but not shown in the drawing: "Clean oil reduces wear". The exact wording of either sign is of no importance to the invention itself.

The upper openings in the cover 16 are circular and permit light to pass to the extensions 17, 10 which have slots 18 in their upper halves. The dotted lines in Fig. 1 show the position of the sample holder when in position for examination, in the slot of the left extension. These extensions 17 are threaded to receive the adjustable 15 members 19, which in turn hold the plano-convex lenses 20, held in position by stops 21.

Referring particularly to Figures 4 and 5, the sample holder 23 is shown folded flat in Fig. 4. The shape and relative size of the sample holder 20 may vary, but its preferred form is that shown in Fig. 4, because only a few drops of oil from the bayonet gauge are necessary to make a splendid test. Fig. 5 shows a top view of the sample holder when opened under slight pressure between 25 the thumb and forefinger, providing a funnel opening. As previously stated, the sample holder is made of transparent material, such as Celluloid and provides an opportunity for any oil company that might sponsor the test, to display their 30 insignia for advertising purposes, as in the central position 22.

In general, the operation of the tester has already been indicated. It is used principally to make a comparison between used oil and clean, 35 unused oil. With the clean sample already installed, the operator has only to take the used oil sample from the bayonet gauge of the engine and insert the sample holder in the proper slot. By now moving the switch to the left, the light 40 back of the used oil sample will at once make the color of the sample quite evident. Further, particles of dirt and other abrasive matter clinging to the side of the sample holder are plainly 45 visible. If the switch is now moved to the other position, the light shines behind the clean sample and the comparison is rendered obvious. After use, the dirty oil sample can be disposed of, and a clean new sample holder used for the 50 next test, eliminating the need of cleaning.

It is immaterial whether the illuminated displays be above or below the samples, and the arrangement of other parts may be changed or parts may be omitted without departing from 55

the spirit of the invention as defined in the following claims.

I claim:

1. In combination with a device for visually examining liquids comprising a manually transportable case having an opening, illuminating means positioned within the case, a slot between the opening and the illuminating means, and a transparent sample holder comprising a pair of separable transparent walls normally having a face to face contact connected along a portion of their peripheral edges to form a holder for the liquid to be examined, the unconnected edges of the said walls forming a mouth through which the liquid can be inserted into the holder when the walls are separated and spread out between the walls into a thin light-transmitting film whereby the holder and the liquid can be inserted in the said slot and light passed through the holder and liquid to permit visual examination of the said liquid.
2. In a device for examining liquids, a case having an observation opening therein, illuminating means within the case and a slot in a wall of the case between the illuminating means and the observation opening, a transparent holder for a sample of the liquid to be examined, the said sample holder comprising a pair of triangular yieldable transparent walls normally tending to have a face to face contact connected along two of the converging edges and the other two edges forming an opening through which the liquid can be inserted in the holder when the walls are separated whereby the walls force the liquid into a thin film, the said converging edges of the sample holder engaging the ends of the slot to support the said holder during examination whereby light may be passed through the transparent holder and liquid and the liquid visually examined.
3. In a device for examining liquids, a case having an observation opening therein, illuminating means within the case and a slot in a wall of the case between the illuminating means and the observation opening, a holder for a sam-

ple of the liquid to be examined comprising a pair of transparent, flexible walls connected together along converging peripheral edges and having another portion of their peripheral edges separable to form a normally closed mouth through which liquid can be inserted into the holder, the said walls of the holder normally being held together due to the inherent flexibility of the said walls, the said walls being separable by the application of edgewise pressure to the said walls to open said mouth whereby upon release of said pressure the walls tend to come together and spread the liquid into a thin film, the said converging edges of the holder engaging the ends of the slot to support the holder in the case between the observation opening and the illuminating means whereby light can be passed through the holder and liquid and the liquid visually examined.

4. In a device for examining liquids, a case having an observation opening therein, illuminating means within the case and a slot in a wall of the case between the illuminating means and the observation opening, a holder for a sample of the liquid to be examined comprising a pair of transparent, flexible Celluloid walls normally having a face to face contact connected together along converging peripheral edges and having another portion of their peripheral edges separable to form a mouth through which liquid can be inserted into the holder, the said walls of the holder normally being held together due to the inherent flexibility of the said walls, the said walls being separable by the application of edgewise pressure to the said walls to open said mouth whereby upon release of said pressure the walls tend to come together and spread the liquid into a thin film, the said converging edges of the holder engaging the ends of the slot to support the holder in the case between the observation opening and the illuminating means whereby light can be passed through the holder and liquid and the liquid visually examined.
